UNITED STATES PATENT OFFICE.

WILLIAM F. ZIMMERMANN, OF MAPLEWOOD, NEW JERSEY, ASSIGNOR TO GOULD & EBERHARDT, OF NEWARK, NEW JERSEY, A CORPORATION OF NEW JERSEY.

SIMPLIFIED HOBBER.

Original application filed August 27, 1924, Serial No. 734,487. Divided and this application filed January 17, 1925. Serial No. 3,021.

This invention relates to hobbing-machines; this application being a division of a parent co-pending application No. 734,487, filed August 27, 1924.

5 In said parent application, there is disclosed a unique machine having a bodily-shiftable stanchion, a non-shiftable work-carrier and balanced drives terminating respectively in worm-wheels for rotating the 10 cutter-spindle and the work-spindles respectively. That structural skeleton is characterized by a notable simplicity; and it is to that subject-matter that this divisional application is devoted; the parent application 15 being relied upon to cover more especially the various control-mechanisms whereby the machine may be, manually and automatically, so controlled as to realize most fully its inherent capacity for a high production 20 of gears.

In devising the structural arrangement herein disclosed, I have undertaken so to improve upon the mechanism of my prior U. S. Patent No. 1,472,767 that the principles of construction thereof may be carried 25 forward and utilized in an even more simple, rigid and sturdy manner, and at the same time render available a machine exhibiting various conveniences in point of an 30 invariable location of the work to keep it uniformly within reach of the user, and at the same time to provide a superior way of supporting the cutter; all in effective relation with a balanced few-part transmission 35 system.

By the term "balanced drive" as used herein is meant a special relationship between the elements connecting the driven cutter-spindle and the driven work-spindle respectively with the common source of power; said relationship being such that neither branch presents more sources of backlash, such as pairs of intermeshing gear-teeth, than the other branch; thereby reducing 40 proportions in vibrations and minimizing the tendency to chatter under the intermittent releases of successive teeth from the work.

To eliminate the intervention of a work-supporting carriage between the bed and the work-supporting spindle is an objective of this invention; this being accomplished by journaling that spindle directly in the bed of the machine near one end and so devis-

ing and mounting the stanchion that it may 55 be shifted as hereinafter explained to provide the adjustment for various diameters of work. Among the advantages derived from the manner of mounting the spindle are (1st) by eliminating the carriage, the 60 axis of the hob may be located closer to the slide-ways of the stanchion and the "overhang" is thus reduced and less vibration can occur in the hob; (2nd) the work-supporting spindle has a more solid support 65 directly in the heavy casting of the bed and hence it exhibits to a pronounced extent the desirable characteristics of an anvil so that the work is supported thereby in a manner 70 well adapted to receive, without manifesting vibration, the hammer-like blows of the successively acting teeth of the hob; (3rd) the work spindle is always located at the same place with respect to the end of the bed and thus is at all times equally within the easy 75 reach of the attendant whether for cutting gears of larger or of small diameters; and (4th) the fixed position of the spindle on the bed enables a larger worm-wheel to be 80 affixed to its spindle and enables the bed casting to be reinforced and made more rigid with the same weight of metal than if clearances for the travel of the enclosed worm-wheel had to be provided.

To take advantage of the otherwise necessary massiveness of the stanchion by utilizing it in a steadyng capacity is likewise within the objective of this invention. The stanchion, which is virtually a part of the bed, has to be provided as a support for the 85 hob and, as the hob is necessarily located some distance from the plane of the bed, the stanchion must be large and, being large, it must be heavy and massive so that it may 90 not flex or quiver under the action of the hob. Now, by making this rather ponderous element capable of being slid on the bed (through an agency such as will be indicated) it has the general characteristics 95 of a shiftable anvil and is, by its very massiveness, capable of absorbing the shocks largely independently of any means for clamping it to the bed. Furthermore, its great weight tends to hold it firmly on the 100 ways of the bed and that weight acts in the same direction as the clamping elements and hence the stanchion admits of being better and more rigidly secured to the bed by

the same clamping force as a relatively thin carriage which naturally tends to deflect and thus localize the clamping pressures. Also, being large, the stanchion provides a base 5 of ample dimensions and those proportions are adequate for the needs of a slidable element and do not have to be enlarged; so that, by eliminating the carriage and thus reducing the number of major elements of 10 the machine, a saving of the equivalent weight of metal may be accomplished and yet a more rigid construction attained. To slide the heavy stanchion, as will be perceived by reference to my parent application 15 a power traverse mechanism may be employed to enable the user to perform that labor without effort; means for accomplishing that initial movement by manual power being also available as shown herein.

20 The aforesaid structural skeleton, with its attendant advantages, has been combined with a simplified system of driving elements organized in an arrangement harmonizing with said structural skeleton and presenting 25 the advantages of a balanced drive; all of which will become manifest by referring to the accompanying drawings, in which:

Fig. 1 is a side elevation of a hobbing-machine showing a fixed work spindle and a 30 shiftable stanchion supporting a hob-carrying head slidable thereon; all in combination with a compatible simplified balanced drive. Fig. 2 is a skeleton of the balanced-drive transmission system for performing the 35 various movements of the working and positioning elements of the machine. Figs. 3 and 4 are rear and front end-elevations, respectively, of the machine showing further details of the manner of combining the balanced drive with the major frame-elements 40 of the machine.

The bed A, in this embodiment, is elongated and positioned horizontally and provides a forward working region in which 45 the work spindle is directly journaled so as to occupy a fixed position, and the bed provides also a rear mechanism-supporting region on which the stanchion is slidably mounted. The work spindle W is shown 50 journaled in fixed bearings A' and it extends downwardly into the interior of the bed as indicated by W' and, at its lower end, carries a worm-wheel W² by which it is driven. The portion of the bed that houses 55 the worm-wheel W² is appropriately enlarged to contain that wheel and, inasmuch as the wheel occupies a fixed position in space, the bed admits of being ribbed and reinforced closely to the wheel and thus 60 made very rigid as will be understood without illustration. It is noteworthy that by thus giving the work spindle a fixed position at the forward end of the bed, it is at all 65 times quickly accessible to the user and it is not at one time further from the end of the

bed than at another as often happens when the work spindle is shiftable in position. The mounting of the spindle is accomplished in a very solid manner with the object of 70 realizing the effect of an anvil so that it virtually supports the work substantially as solidly as though it was clamped to the bed itself and, in consequence, the tendency to vibrate and chatter is reduced to a minimum.

The stanchion S is in the nature of a heavy box-like casting which is provided with slideways S' and S² at right angles to one another; the slideways S' resting on the 80 slideways S² provided by the surface of the bed and arranged to permit the heavy stanchion to be slid towards and away from the axis of the work spindle for the purpose of determining the diameter of the gear G to be cut by the machine. The purpose of the transverse slideways S² is to support and 85 guide a head H which is thus shiftable in parallelism with the axis of the work-spindle so that the cutter or hob (which is carried by the head) may in the course of the 90 feeding movement cut the teeth of the gear G. It will be understood that this head H is suitably gibbed to the slideways S² and, in 95 order to counterbalance the weight of the head H, a counterweight H⁴ may be arranged to rise and descend in an appropriate well provided by the stanchion S; conventional ropes and pulleys H² and H³ being provided as will be understood.

It is to be noted that the stanchion, being 100 heavy and massive, is in effect a part of the solid bed itself because when clamped down to that bed, it becomes very solid therewith owing to the action of the clamps augmented by the weight of the stanchion and 105 by reason of the fact that the base of the stanchion S is very extensive so as to resist effectively such overturning forces as result from the pressure of the hob against the work during the tooling operation. It 110 will likewise be noted that, in cutting spur gears, the stanchion requires to be shifted only when a change is to be made in the diameter of the spur gears being cut (which ordinarily would be quite infrequent) and 115 it will also be noted that the shifting of the stanchion does not reduce the facility of access of the user to the work spindle and does not interpose obstructions when brought closer to that spindle. It will also be noted 120 that the slideways S' at the base of the stanchion runs to a region substantially underlying the head H so that this construction avoids the objectionable overhang which is necessitated whenever the work spindle 125 is mounted on a carriage which slides on the bed.

The simplified transmission system for 130 rotating both the work spindle and the hob, and for progressively feeding the head H,

and for shifting the position of the stanchion S, and for varying the rates of rotations and for shifting the parts quickly or slowly as the case may be, will now be 5 described.

This transmission is in the nature of a balanced drive and comprehends an intermediate splined shaft X and two main transmission shafts Y and Z: the hob-driving shaft Y being also splined. These two shafts are disposed at right angles and the intermediate shaft is parallel with one of them; the latter being in this embodiment the non-splined shaft that communicates motion to the work spindle. The intermediate shaft receives the power in the first instance; this being accomplished by the power-line consisting of a pulley P or other prime mover, the power shaft P' and appropriate gears such, for example, as the two spur gears P² and P³ and the two angle gears P⁴ and P⁵.

The hob-driving splined transmission shaft Y is journaled in the shiftable stanchion so as bodily to travel therewith in a direction parallel with the intermediate shaft and, at its lower end, it is provided with an angle gear y which meshes with a shiftable angle gear x' which is splined to the intermediate shaft X. The cutter C is mounted on a spindle c which is journaled in the head H at an appropriate angle to compensate for the helix-angle of the hob used for cutting the spur teeth. This angle may be in the neighborhood of five degrees for a single thread hob or ten degrees for a double thread hob. This angle being fixed and not of great magnitude admits of a very simple and direct driving connection 30 between the spindle c and the splined transmission shaft Y. That is to say, a worm y' is splined to the shaft Y and is journaled in the head H so that, as the head moves up or down, the worm will be correspondingly shifted on the shaft Y and a worm-wheel c' is affixed to the end of the spindle c and its teeth are so cut, with a skew-gear effect, that the meshing will be perfect although the worm and worm-wheel are at an angle to each other.

The other non-splined transmission shaft Z is journaled in the bed of the machine and has a worm z' affixed thereto for driving the spindle W through the worm-wheel W'. The single pair of change gears x² and z² establish the driving relation between the intermediate power shaft X and the transmission shaft Z; it being observed that this arrangement provides a balanced drive in which the four gears W², z', z² and x² transmit the motion to the work spindle, and likewise four gears c', y, y' and x' transmit the motion to the cutter.

To start the machine, the power lever B is actuated. This shifts the collar 8 and

slides a long key 9 (which is translatable counter-sunk in the shaft P') and this key actuates a suitable clutch (not shown) between the prime-mover P and the shaft P'. The transmission elements previously described are then maintained in motion by the power imparted to the intermediate shaft and the cutter and the work are both revolved at the relative rate determined by the two change gears z² and x². 70

To manually shift the stanchion, a hand-wheel V (provided with graduations or micrometer adjustments) is affixed to a shaft that carries an angle gear V' which meshes with an angle gear V² which is splined to the screw S⁵ and enables it to be turned by hand. The above described manual means enables the user very readily to bring the stanchion to any desired position with respect to the work-spindle for cutting spur gears. 75

To feed the cutter head, the parts will be in the positions and relations shown; the clutch F⁷ being engaged with the result that the shaft F⁶ is connected to the shaft Q⁷ 90 and runs at the rate determined by the feed change-gears designated generally by 7. The feeding motion is conveyed by a transmission consisting of an angle gear 1 mounted on the shaft Z and meshing with an angle gear 2 affixed to the shaft 3. A worm 4 on that shaft drives a worm-wheel 5 which turns the shaft 6 and, through appropriate change-gears designated generally by 7, the gear r² is driven and this gear is affixed to a sleeve r which is loosely mounted on the shaft Q⁷ but may be connected thereto by the clutch-teeth r' by bodily shifting the sleeve r to connect the parts described. Angle gears F⁵ and F⁴ transmit the motion to the shaft F³ which is journaled in the stanchion and, at its upper end, has a gear F² which meshes with a gear F' which is a unit with a nut that turns about the non-rotatable feed-screw F. That feed-screw 100 is affixed to the head H and is caused to move up or down, as the case may be, by the rotating nut and, in this manner, the cutter journaled on the head H is caused to feed downwardly whenever the parts are connected up as described. To avoid needless reference to certain features covered by the parent application, they have been omitted from the drawings. For instance, the power traverse extending from gear Q 110 to gears Q⁴ and Q⁵; also the means for manipulating the clutches r, Q⁶ and F⁷; all of such means having been fully set forth in the parent case but forming no special part of this divisional subject-matter. 115

Without further analysis, the foregoing will so fully reveal the gist of this invention that others can, by applying current knowledge, readily adapt it for various utilizations by retaining one or more of the 120 125 130

features that, from the standpoint of the prior art, fairly constitute essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A balanced-drive hobbing-machine comprising a bed; a relatively heavy stanchion shiftably supported thereon; a work-supporting spindle non-shiftably journaled in said bed near one end thereof; a splined shaft and a parallel transmission shaft, each journaled on said bed transversely to said spindle; a pair of spur change gears connecting said two shafts; a splined transmission shaft journaled on said stanchion parallel with said spindle; a head slideable on said stanchion; a hob-supporting spindle on said head; a pair of angle gears connecting said hob spindle with said splined transmission shaft, one of said angle gears being splined to said shaft; a pair of angle-gears connecting said shaft to said first-mentioned shaft, one of said gears being splined to said first-mentioned shaft; and a pair of angle gears connecting said parallel transmission shaft with said non-shiftable work spindle.
2. A balanced-drive hobbing-machine combining a bed; a work-supporting spindle occupying a fixed position on said bed; a heavy stanchion shiftably mounted on said bed; a hob-supporting spindle slidably carried by said stanchion; a transmission connecting said spindles and consisting of but three transmission shafts, the one being a work-driving shaft, the other a hob-driving shaft and the third being an intermediate shaft, said intermediate shaft being splined and arranged parallel to the work-driving transmission shaft and transversely to the hob-driving transmission shaft; the adjacent ends of said two parallel shafts being directly connected by two change gears of the spur-tooth type, the hob-driving shaft being splined; an angle-gear slideable on said intermediate shaft; said hob-driving shaft being geared at one end directly to said spindle and at its other end directly to said slideable angle-gear; a prime-mover geared directly to the intermediate shaft whereby the power for driving said spindles will be derived from the respective ends thereof; and means for effecting a progressive relative translation between said spindles in a direction parallel with the work-supporting spindle.
3. A hobbing-machine combining a hob-supporting spindle and a work-supporting spindle arranged transversely thereto, a first

splined transmission shaft arranged transversely to said hob-supporting spindle; a worm-splined thereon; a second non-splined transmission shaft arranged transversely to said work-supporting spindle; a worm affixed thereon; the worms on said shafts being in mesh with worm-wheels on the respective spindles; and a third splined transmission shaft arranged parallel with the second of said transmission shafts and having splined thereon one of a pair of bevel-gears directly connecting together both of the splined transmission shafts; two intermeshing spur-gears, the one secured directly to said third shaft and the other directly to the second transmission shaft parallel therewith; and means for effecting a progressive relative translation between said spindles in a direction parallel with the work-supporting spindle.

4. A hobbing-machine combining a bed; a stanchion shiftable thereon; a hob-supporting spindle shiftable on said stanchion; a work-supporting spindle non-shiftably journaled in said bed; a transmission connecting said spindles and consisting in serial relation first of a pair of angled-gears, second of another pair of angled-gears, third of a pair of spur-gears, and fourth of a pair of angled-gears; a splined transmission shaft directly connecting said first two pairs of angled gears; another splined transmission shaft directly connecting said second and third pairs of gears; a third non-splined shaft connecting the last two pairs of gears; a prime mover connected to an intermediate portion of said transmission train, whereby the motion to the spindles will be transmitted in two paths, the one being through the second and first pairs of gears, and the other being through the third and fourth pairs of gears; and means for effecting a progressive feed of said hob-supporting spindle along said stanchion in a direction parallel with the work-supporting spindle.

5. A hobbing-machine combining a hob-supporting spindle and a work-supporting spindle; means for bodily shifting said hob-supporting spindle in a direction transverse to the axis of the other to adjust the offset relation between said spindles; a transmission connecting said spindles and consisting in serial relation first of a pair of angled-gears, second of a splined shaft, third of a pair of angled-gears, fourth of another splined shaft, fifth of a pair of spur-gears, sixth of a transmission shaft, and seventh of a pair of angled-gears, one of the gears of the first pair being slidably shiftable on said first mentioned splined shaft, and one of the gears of the next mentioned pair being splined on said second mentioned splined shaft, said shaft being arranged to extend in a direction transverse to the axis of the work-supporting spindle; and means

for effecting a progressive feed of said hob-supporting spindle in a direction parallel with the work-supporting spindle.

6. A hobbing-machine combining a hob-supporting spindle; means for shifting said spindle laterally in either one of two transverse directions; a work-supporting spindle; a transmission connecting said spindles and consisting of but three shafts and eight gears; a prime-mover geared directly to one of the intermediate parts whereby the power for driving each of said spindles will be transmitted by but four gears, one of the four gears used for propelling the laterally shiftable hob-supporting spindle having its axis extending in a direction transverse to the axis of said work-supporting spindle and being splined to the shaft on which it is mounted; and means for effecting a translation of said hob-supporting spindle in directions parallel with and transverse to the work-supporting spindle.

7. A hobbing-machine combining a hob-supporting spindle and a work-supporting spindle; a first splined shaft arranged transversely to one of said spindles; an angle gear slidably mounted on one end of said splined shaft and a spur-gear detachably secured directly to its other end; a second splined shaft arranged transversely to said first shaft; an angle gear on one end of said second splined shaft and meshing directly with said first-mentioned angle-gear; a worm splined to said second splined shaft; a worm-wheel meshing therewith for propelling one of said spindles, means including a detachable spur-gear meshing directly with said first-mentioned spur-gear for propelling the other spindle, and means for effecting a progressive relative translation between said spindles in a direction parallel with said work spindle.

8. A hobbing-machine combining a hob-supporting spindle, and a work-supporting spindle; a splined shaft arranged transversely to said spindles, an angle gear slidably mounted at one end of said splined shaft and a spur-gear detachably secured directly to its other end; two shafts arranged transversely to said spindles respectively, but one of said two shafts being splined, an angle gear secured to one end of the splined one of said shafts and meshing directly with said first mentioned angle gear, a detachable spur-gear secured directly to one end of the other of said two shafts and meshing directly with said first-mentioned spur-gear; a first worm splined to said splined shaft, and a second worm secured to the other of said two shafts; worm-wheels meshing directly with said worms for propelling said spindles, and means for effecting a progressive relative translation between said spindles in a direction parallel with said work spindle.

9. A balanced-drive hobbing-machine comprising a bed; a relatively heavy stanchion shiftably supported thereon; a work-supporting spindle non-shiftably journaled in said bed near one end thereof; an intermediate splined shaft and a parallel transmission shaft, each journaled on said bed transversely to said spindle; a pair of spur change gears connecting said two shafts; a splined transmission shaft journaled on said stanchion parallel with said spindle; a head slideable on said stanchion; a hob-supporting spindle mounted at a fixed angle on said head; a single pair of skew angle gears connecting said hob spindle with said splined transmission shaft, one of said angle gears being splined to said shaft; a pair of angle-gears connecting said shaft to said intermediate shaft, one of said gears being splined to said intermediate shaft; and a pair of angle gears connecting said parallel transmission shaft with said non-shiftable work spindle.

10. A balanced-drive hobbing-machine combining a bed; a work-supporting spindle occupying a fixed position on said bed; a heavy stanchion shiftably mounted on said bed; a hob-supporting spindle slidably carried by said stanchion; a worm-wheel of the skew gear type on said spindle; a transmission connecting said spindles and consisting of but one intermediate and two transmission shafts, said intermediate shaft being splined and arranged parallel to the work-driving transmission shaft and transversely to the hob-driving transmission shaft; the adjacent ends of said two parallel shafts being directly connected by two change gears of the spur-tooth type, the hob-driving shaft being splined; a worm slideable thereon; angle-gear slideable on said intermediate shaft; said hob-driving shaft being through said skew worm and worm-wheel geared at one end directly to said spindle and being at its other end directly to said slideable angle-gear; a prime-mover geared directly to the intermediate shaft whereby the power for driving said spindles will be derived from the respective ends thereof; and means for effecting a progressive relative translation between said spindles in a direction parallel with the work-supporting spindle.

11. A hobbing-machine combining a hob-supporting spindle and a work-supporting spindle arranged transversely thereto, a first splined shaft arranged transversely to said hob-supporting spindle; a worm-splined thereon; a second non-splined shaft arranged transversely to said work-supporting spindle; a worm affixed thereon; the worms on said shafts being in mesh with worm-wheels on the respective spindle, the worm and worm-wheel for driving the hob being of the skew type; and a third splined shaft

arranged parallel with the second of said transmission shafts and having splined thereon one of a pair of bevel-gears directly connecting together both of the splined transmission shafts; two intermeshing spur-gears, the one secured directly to said third shaft and the other directly to the second transmission shaft parallel therewith; and means for effecting a progressive relative translation between said spindles in a direction parallel with the work-supporting spindle.

12. A hobbing-machine combining a bed; a stanchion shiftable thereon; a hob-supporting spindle mounted at a fixed angle thereon and shiftable on said stanchion; a work-supporting spindle non-shiftable journaled in said bed; a transmission connecting said spindles and consisting in serial relation first of a pair of angled-gears of the skew type, second of a pair of angled-gears, third of a pair of spur-gears, and fourth of a pair of angled-gears; two splined transmission shafts directly connecting said first three pairs of gears in series; a third-non-splined shaft connecting the last two pairs of gears; a prime-mover connected to said transmission train, whereby the motion to the spindles will be transmitted in two paths, the one being through the second and first pairs of gears, and the other being through the third and fourth pairs of gears; and means for effecting a progressive feed of said hob-supporting spindle along said stanchion in a direction parallel with the work-supporting spindle.

13. A hobbing-machine combining a hob-supporting spindle and a work-supporting spindle; means for bodily shifting said hob-supporting spindle in a direction transverse to the axis of the other to adjust the off-set relation between said spindles; a transmission connecting said spindles and consisting in serial relation first of a pair of angled-gears of the skew type, second of a pair of angled-gears, third of a pair of spur-gears, and fourth of a pair of angled-gears, two splined transmission shafts directly connecting the first and second and the second and third pairs of gears in series, one of the gears of the first pair being slidably shiftable on said first shaft, and one of the gears of the second pair being splined on said second shaft, said shaft being arranged to extend in a direction transverse to the axis of

the work-supporting spindle; a third transmission shaft connecting said third and said fourth pairs of gears and means for effecting a progressive feed of said hob-supporting spindle in a direction parallel with the work-supporting spindle.

14. A hobbing-machine combining a hob-supporting spindle and a work-supporting spindle; a first splined shaft arranged transversely to one of said spindles; an angle gear slidably mounted on one end of said splined shaft and a spur-gear detachably secured directly to its other end; a second splined shaft arranged transversely to said first shaft; an angle gear on one end of said second splined shaft and meshing directly with said first-mentioned angle-gear; a worm splined to said second splined shaft; a worm-wheel meshing therewith for propelling one of said spindles, said worm and worm-wheel being of the skew type; means including a detachable spur-gear meshing directly with said first-mentioned spur-gear for propelling the other spindle, and means for effecting a progressive relative translation between said spindles in a direction parallel with said work spindle.

15. A hobbing-machine combining a hob-supporting spindle, and a work-supporting spindle; a splined shaft arranged transversely to said spindles, an angle gear slidably mounted at one end of said splined shaft and a spur-gear detachably secured directly to its other end; two shafts arranged transversely to said spindles respectively, but one of said two shafts being splined, an angle gear secured to one end of the splined one of said shafts and meshing directly with said first mentioned angle gear, a detachable spur-gear secured directly to one end of the other of said two shafts and meshing directly with said first-mentioned spur-gear; a first worm splined to said splined shaft, and a second worm secured to the other of said two shafts; worm-wheels meshing directly with said worms for propelling said spindles, the worm-wheel for the hob-spindle being of the skew type; and means for effecting a progressive relative translation between said spindles in a direction parallel with said work spindle.

In witness whereof, I have hereunto subscribed my name.

WILLIAM F. ZIMMERMANN.
